Primary Examiner — T Chase Nelson*(74) Attorney, Agent, or Firm* — Marshall A. Lerner; Steven J. Kim; KLEINBERG & LERNER, LLP(57) **CLAIM**

The ornamental design for a shoe sole, as shown and described.

DESCRIPTION

FIG. 1 is a side elevation view of a shoe sole; and, FIG. 2 is a bottom plan view of a shoe sole thereof. The broken lines shown in the drawing represent environmental structure in the form of a shoe upper as well as portions of the shoe sole that form no part of the claimed design. The surfaces devoid of shading lines are not claimed.
